R. S. GRAHAM.
HEEL FOR FOOTWEAR.
APPLICATION FILED MAR. 6, 1912.

1,084,268.

Patented Jan. 13, 1914

UNITED STATES PATENT OFFICE.

ROBERT S. GRAHAM, OF NEW YORK, N. Y., ASSIGNOR, BY DIRECT AND MESNE ASSIGNMENTS, OF ONE-THIRD TO WILLIAM E. GRAHAM, OF NEW YORK, N. Y., AND ONE-THIRD TO RAYMOND P. MORSE, OF BROOKLYN, NEW YORK.

HEEL FOR FOOTWEAR.

1,084,268.

Specification of Letters Patent. Patented Jan. 13, 1914.

Application filed March 6, 1912. Serial No. 681,958.

To all whom it may concern:

Be it known that I, ROBERT S. GRAHAM, a citizen of the United States, residing in the city of New York, borough of Manhattan, county and State of New York, have invented a certain new and useful Heel for Footwear, of which the following is a specification.

This invention is a heel for boots, shoes and the like, and the object is to relieve the jar on the muscles of the foot and leg which follows when the heel strikes the ground.

Many attempts have been made to solve this problem, but so far as I am aware, all prior heels have been defective for one cause or another. Among the forms of heels best known to the public, are all rubber heels, and composite leather and rubber heels. All rubber heels, while affording a desirable cushion, are difficult and insecure of attachment, do not wear well, and soon become as objectionable to the wearer as are the hard unyielding heels, for the reason that they become too soft and easy. Heels composed of leather lifts with an interposed rubber lift have not been attached in such manner that the bottom layer is precluded from becoming loosened and having a tendency to catch against staintreads, gratings, etc., so as to form a menace to the wearer. Obviously, a composite heel should not be nailed in the same way as a hard stiff leather heel, for to do so would be to render the composite heel equal in hardness and rigidity to the all leather heel. Accordingly, it has been proposed to cement the interposed rubber layer to the upper part of the heel, and to attach the bottom leather lift to the heel by nailing the front part to said heel, thus leaving the bottom lift unattached for practically its length and width except at said front edge. It is at once apparent that the bottom lift does not possess that security of attachment which is so essential to a heel designed to withstand rough usage and wear, for the reason that such lift is liable to catch in staintreads and in gratings, etc., thus pulling the tread easily off the heel, besides tending

to trip the wearer, resulting in possible injury.

I am aware that it has been proposed to employ a bottom lift composed partly of rubber and partly of leather, and, further, that it has been proposed to fasten an all rubber bottom lift to a heel by the use of a leather binding fitted in a recess of the heel and fastened to the front and side portions of said heel; but neither of these devices is satisfactory for several practical reasons.

The present invention embodies a heel composed of all leather lifts, or of leather and rubber lifts, so nailed together that the bottom lift is capable of a certain degree of action independently of the upper part of the heel, thus producing a heel the lifts of which are not only securely attached, but the heel is capable of use in such manner that the jar is taken off the foot and leg. The lower part of the heel is fastened at its front edge, and along the two side edges for a part of the way, by nails which attach said lower part securely and rigidly to the upper part, said lower part being free or unattached at the rear and for a part of the two side edges. The lower part cannot become detached accidentally, but the rear of said lower part is capable of action independently of the upper part. Practical experience has conclusively shown that a heel constructed in accordance with this invention operates in a manner to relieve the shock or jar when walking, and that the lower part will not become torn off even though the heel is caught in a grating, etc.

In the accompanying drawings, I have illustrated different embodiments of the invention, but the constructions shown therein are to be understood as illustrative only and not as defining the limits of the invention.

Figure 1 is a plan view of a heel embodying the invention. Fig. 2 is a vertical section of a heel composed wholly of leather layers. Fig. 3 is a similar section of a heel composed of leather layers and a rubber or equivalent cushion material interposed between certain leather layers. Fig. 4 is a plan view showing one method of nailing

the lower part of the heel at its front edge, the two side edges, and across the breast. Fig. 5 is a plan view illustrating another method of nailing the lower part of the heel 5 to the upper part thereof.

A designates the rear part of a sole, and B, C designate the upper and lower parts of a heel. The upper part of the heel is composed of a series of leather lifts b which 10 are fastened solidly to sole A by any desired arrangement of nails b' driven through the leather lifts or into the sole in the usual manner. The height of part B forming a part of the heel is not equal to the height 15 of the finished heel, but the complete heel is composed of parts B, C, the latter being attached to the part B by nailing in the novel manner shown in Figs. 1, 4 or 5.

Part C of the heel may consist of a single 20 layer of suitable material, but it is shown in Figs. 2 and 3 as composed of lifts c, c'. Each lift consists of a single continuous piece of leather of suitable size and thickness. The two lifts c, c' are attached together at the rear edge thereof by wear short nails d, but as shown in Figs. 2 and 3, these wear nails do not extend through the lift c, and, accordingly, these wear nails do not enter the upper part B of the heel. 25 Part C is attached to part B by nails e, f, g. Nails e are driven in a row through the front edge of part C so as to enter upper part B to any desired extent. Nails f are driven through the lower part C for a de- 30 sired distance along one side edge thereof, whereas nails g are likewise driven through lower part C, and for a desired distance, along the opposite side edge thereof, whereby nails e, f, g, operate to firmly attach 35 lower part C at its front and respective side edges to the upper part B in such a manner that the rear and side edges of part C are not attached in any way to the upper part B. By this construction the rear of 40 lower part C is capable of action independently of upper part B, and this independent action is obtained in all leather heels, like Fig. 2, or in a composite heel of the form shown in Fig. 3, wherein the heel is com- 45 posed partly of leather and a layer of cushion material, such as rubber or its equivalent, indicated at D. The leather lifts composing the upper part B are secured firmly together, in the manner heretofore described, 50 by nails b', whereas a cushion layer D of rubber, or its equivalent, is applied to the under face of part B. The lower part C is fitted against the under side of cushion layer D, and these two elements, to wit, lower part 55 C and cushion D are firmly attached to upper part B by nails e, f, g, driven in the manner heretofore described, through part C and cushion layer D. In practice, cushion layer D constitutes an element of the upper

part B, but the lower part C is capable of 65 the independent action at its rear relative to the cushion layer D when the latter is employed in the construction of the heel of Fig. 3.

The method of nailing shown in Fig. 4 70 is essentially the same as that heretofore described, to wit, a row of nails e is driven through the forward part of the heel, nails f, g are driven through the forward part 75 of the heel at the respective side edges, and if desired, an additional row of nails h is driven through part C across the breast thereof, the rear of lower part C being unattached and capable of the independent action relative to the upper part. The number of nails in the front edge and forward parts of heel part C is not material, and in Fig. 5 there is shown a single front nail e', and two nails f', g' at the forward side edges of heel part C. While the arrangement of Fig. 5 may answer certain practical requirements, it is preferred to employ the nails arranged in rows e, f, g, substantially as shown in Figs. 1, 2 and 3 of the drawings.

The lower part C of the heel may consist 80 of a single layer composed of a continuous piece of leather, but to provide for increased service of the heel it is preferred to employ two leather layers each composed of a single piece of material and said layers being 85 united to each other at the rear by wear nails d. Obviously, the wear nails are not essential.

From the foregoing description taken in connection with the drawings it will be seen 90 that I have provided a heel, composed of two parts, an upper part and a lower part, the upper part being rigidly and firmly attached to the shoe, whereas the lower part is attached in a peculiar manner to the 95 upper part. The lower part is fastened at its front edge and for a part of the two side edges to the upper part B so that the lower part C of the heel cannot become accidentally torn off the heel, but at the same time 100 the rear of said lower part C is capable of such independent action relative to the upper part that a cushion is effectually produced between the upper and lower parts B, C at the rear of the heel; thereby relieving 105 the muscles of the foot and leg from the shock and jar which necessarily follows the impact of the heel with the ground.

Having thus fully described the invention, what I claim as new, and desire to secure by Letters Patent is:

A heel embodying an upper part secured solidly to a shoe, a lower part the rear of which is free to act independently of the upper part, and attaching nails positioned at 115 the front edge and at the respective side edges of the upper and lower parts, the side nails extending in rows from the front to-

ward the rear and for substantially half the length of the heel, said nails at the front and sides operating to so securely fasten the lower part that it cannot become accidentally detached and said lower part being unattached at its rear for the purpose of relieving the jar incident to the contact of the heel with the ground.

In testimony whereof I have signed my name to this specification in the presence of two subscribing witnesses.

ROBERT S. GRAHAM.
